(57) **CLAIM**

The ornamental design for a control panel for a medical refrigerator, as shown and described.

DESCRIPTION

FIG. 1 is a perspective view of a control panel for a medical refrigerator of the present invention;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom view thereof; and,
FIG. 8 is a perspective view thereof shown in an environment.

The even broken lines show parts of the control panel for a medical refrigerator that represent unclaimed subject matter and form no part of the claimed design.

1 Claim, 8 Drawing Sheets(56)
